UNITED STATES PATENT OFFICE.

CLYDE WILLIAM STUART, OF MELROSE HIGHLANDS, MASSACHUSETTS.

DISPLAY DEVICE.

Application filed November 24, 1923. Serial No. 676,706.

To all whom it may concern:

Be it known that I, CLYDE WILLIAM STUART, a citizen of the United States, and a resident of Melrose Highlands, in the county of Middlesex and State of Massachusetts, have invented an Improvement in Display Devices, of which the following description, in connection with the accompanying drawings, is a specification, like characters on the drawings representing like parts.

This invention relates to a display device and has for its object to provide an inexpensive simple device particularly, though not exclusively, adapted for displaying articles such, for example, as neckties and collars in the relation in which they are to be worn.

Referring to the drawings in which I have shown merely for illustrative purposes certain embodiments of the invention:

Fig. 1 is a front elevation with parts in section of the preferred form of device with a collar and necktie indicated in dotted lines;

Fig. 2 is a vertical enlarged section of the upper or holder portion of the device;

Fig. 3 is a detailed front elevation of a modified form of holder; and

Fig. 4 is a side elevation of the holder part of said modified form.

In the accompanying illustrations I have, for convenience, shown the invention in the form of a necktie and collar holder but it is to be understood that the invention is not limited to this particular application.

In its preferred construction the invention involves a base member or standard 1 having an upstanding part 2 at least the upper end of which is of tubular form at 3 to receive the stem portion 4 of the necktie and collar supporting member, the part 4 being preferably arranged to fit the hollow portion of said upstanding part 2 and to have vertical adjustment therein, it being held in the desired position relatively to said upstanding part herein by a thumb screw 5.

The stem portion 4 is provided at its upper end with a cross piece 6 which, in normal usage, constitutes a support over which the narrow string part of the tie indicated at 7 in dotted lines, is laid, said string part being next bent across beneath said cross piece around the stem of the

holder and then returned to the rear and 55 looped through that portion wound about said stem so as to form the usual knot 8, the laterally projecting portions of said cross piece serving the part of the narrow string portion of a four-in-hand tie when 60 being worn.

A collar holder 9 is also provided, it being herein composed of rearwardly extending resilient arms 10 and 11 constituting the extreme portions of said cross piece, said 65 resilient members curving rearwardly yielding to embrace substantially the greater part of a band 12 of a collar 13, said resilient members being arranged to extend between the folds of a turned down collar so as 70 naturally to position the collar in the relation to the tie which it would assume in normal usage.

To insure the locating or positioning of the knot of the tie at the proper distance 75 below the upper edge of the collar the arms 10 and 11 of the cross piece 6 are herein offset upwardly at points 14, 14 preferably equidistant from the center line of the stem 4 so that the remaining portions of the collar holder will fit snugly within the fold of the collar, while the lower part of said cross piece covered by the knot of the tie lies the proper distance below the upper or folded edge of said collar.

The resilient members 10 and 11 are preferably bow shaped and, in their normal unstressed positions, when detached from a collar, rest with their outer extremities in substantially close proximity so that, in applying the holder to a collar, the tension of said arms or extensions will cause said arms to press firmly against the collar band, thus holding the latter in place.

The cross piece 6 and its arms 10 and 11 95 may be formed in any appropriate manner but in the preferred form of the invention said cross piece 6 has been shown composed of separate material from that of the stem 4 and this material is preferably wire bent at its central part to form a depending tongue 15 adapted to facilitate the positioning and holding of said cross piece in proper relation to said stem or body portion 4. The latter part may also be constructed 100 in different ways and from a variety of materials, but herein it is formed from metal, the lower portion of which is adapted

to fit the recess in the tubular portion 3 of the standard or base permitting vertical adjustment of the holder within said standard. It is desirable that the upper portion of the 5 stem 4 be bent or deflected rearwardly herein at 16 to cause the body of the necktie supported thereon, more naturally to assume the shape which it assumes when being worn, thus to more pleasingly display and show 10 off the same.

To facilitate the bending of the member 4 and still retain the proper shape for fitting said stand, said stem is preferably constructed of round rod with the standard- 15 engaging portion retaining its original form while the upper curved or bent part is preferably flattened as shown at 17.

Obviously this flattening process may be done in numerous ways one of which may 20 be by stamping and when so treated naturally more or less of the metal will be displaced laterally, thus making the flattened portion wider than the portion entering the standard.

25 If desired, the edges of said flattened portion 17 may be ground off or otherwise removed to correspond in width with the diameter of the lower or unstamped part of said stem 4, preferably leaving the extreme 30 upper end the full width as shown at 18, which latter is then bent double at 19 over the tongue 15 thereby firmly securing the cross piece to the upright part 4.

To further insure the retention of the 35 parts 19 and 15 in permanent relation they may be secured by soldering or otherwise.

40 Figs. 3 and 4 illustrate a modified form of collar holder wherein the cross piece 20, instead of terminating in a short tongue 15, distends into a considerably larger tongue 21 preferably joining with a stem 25 capable of being inserted in the hollow standard 13.

45 To accomplish this result the depending parts of the wires forming said tongue 21 are twisted at 22 for a short distance adjacent to the cross piece to insure a proper binding together of the two arms of the cross piece and these two wires below said 50 twisted part are then slightly separated to form an elongated opening or slot 23 through which screws 24 are inserted to attach said tongue preferably to the back flattened face of the upper part of said stem 25 (see Fig. 4) which is herein adapted to be adjustably secured with the tubular part 3 of said standard as aforesaid, the tongue 21 being forwardly offset at 21' to bring the tie in front of said tongue.

60 With this construction it will be obvious that the part 21, the two wires forming which are integrally united at their lower ends, may be adjusted relatively to the rod 25 by varying the length of the tongue 21 65 to form the required length of slot 23.

The type of tie to which reference has generally been made in the foregoing description is the four-in-hand tie, so-called, but is distinctly to be understood that the device is equally adapted for and capable 70 of displaying a bow tie. Therefore in Fig. 3 a bow has been indicated in dotted lines. In order to facilitate the placing of a bow tie upon the holder the twisted part 22 of the tongue 21 is short enough to permit the 75 string of the tie to be laid over the cross piece 20 and through the upper end of the slot 23 between the sides of said tongue after which it is tied into a knot and the 80 bow formed in the usual manner, any superfluous material in said string being looped in any suitable manner at the rear of the holder.

Obviously the same result may be secured 85 from the form shown in Figs. 1 and 2 by providing an appropriate opening at a distance below the cross piece and desirably for this purpose the upper end of the stem 4, which has been left its full width after 90 flattening of the rod from which said stem is produced, is slotted at 26, this part being entirely concealed when a four-in-hand knot is formed upon the holder and only 95 a portion of the same being shown when a bow tie is supported thereon.

Having thus described certain illustrative embodiments of my invention, I desire it to be understood that although specific terms are employed they are used in a generic and descriptive sense and not for purposes of limitation, the scope of the invention being set forth in the following 100 claims.

Claims:

1. In a display device, in combination, a 105 base portion, a stem adjustably mounted in said base portion having a portion of its length flattened and laterally deflected, a cross piece having a depending tongue embraced by the upper extremity of said stem and forming a necktie support, the extremities of said cross piece being curved laterally and upwardly inclined to embrace and support the neck band of a collar in 110 normal relation to said tie.

2. In a display device, in combination, a stem and a cross piece secured to said stem and having its extremities bent rearwardly in normal contracted relation for embracing and holding a collar, the central portion of said cross piece being depressed to support the knot of a tie a selected distance below the edge of a collar supported by said holder.

3. A display device comprising a transverse member, an upright adjustable supporting standard secured to said transverse member and constituting therewith, means over and about which to form the knot of a tie, and means constituting a part of and 125 130

extending upwardly from said transverse member adapted to enter and engage the fold of a turn down collar and maintain said collar in normal elevated wearing relation to said tie.

4. In a display device, in combination, a stem and a cross piece secured to said stem and having its extremities bent rearwardly in normal contracted relation for embracing and holding a collar, the central portion of said cross piece being depressed and constituting, together with the adjacent portion of said stem, a tie holder adapted to position the knot of said tie a selected distance below the edge of the collar, said tie holding portion of said stem being con-

cealed by the knot and forwardly offset from the body of said stem.

5. In a display device, a collar holder having oppositely bowed resilient arms to 20 embrace the band of the collar, the central portion of said collar holder being depressed and provided with a tongue and a stem having an upper extremity adapted to embrace said tongue and constituting, 25 with the central portion of said collar holder, a form for positioning and maintaining the knot of a tie in normal relation to the collar.

In testimony whereof, I have signed my 30 name to this specification.

CLYDE WILLIAM STUART.
